CLAIM

The ornamental design for a chair, as shown and described.

DESCRIPTION

FIG. 1 is a top perspective view of a chair;

FIG. 2 is a front view thereof;

FIG. 3 is a back view thereof;

FIG. 4 is a side view thereof, for which the mirrored image would depict the opposite side view thereof;

FIG. 5 is a top view thereof; and,

FIG. 6 is a bottom view thereof.

1 Claim, 6 Drawing Sheets
